US00D541922S

(12) **United States Design Patent** (10) **Patent No.:** **US D541,922 S**
Wefler et al. (45) **Date of Patent:** ** *May 1, 2007

(54) **DIFFUSER**

(75) Inventors: **Mark E. Wefler**, Racine, WI (US);
Jeffrey L. Harwig, New Berlin, WI (US); **Stefano Deflorian**, Martignano (IT); **Alessio Giovannelli**, Trento (IT)

(73) Assignee: **S.C. Johnson & Son, Inc.**, Racine, WI (US)

(*) Notice: This patent is subject to a terminal disclaimer.

(**) Term: **14 Years**

(21) Appl. No.: **29/226,812**

(22) Filed: **Mar. 31, 2005**

(51) LOC (8) Cl. **06-01**

(52) U.S. Cl. **D23/366**

(58) **Field of Classification Search** .... 392/386, 392/390-394, 398, 401, 403, 405-406; 239/135-136, 239/34, 35, 56-58, 37, 41, 42, 60; 261/DIG. 17, 261/DIG. 65, DIG. 88, DIG. 89; D23/355-369

See application file for complete search history.

(57) **CLAIM**

The ornamental design for a diffuser, as shown and described.

DESCRIPTION

FIG. 1 is a front isometric view of the diffuser;
FIG. 2 is a back isometric view thereof;
FIG. 3 is a front elevational view thereof;
FIG. 4 is a first side elevational view thereof;
FIG. 5 is a back elevational view thereof;
FIG. 6 is a plan view thereof; and,
FIG. 7 is a bottom elevational view thereof.
FIG. 7 is provided for context only and forms no part of the claimed design. Also, structures shown in broken lines form no part of the claimed design.
The structures shown in broken lines are for illustrative purposes only and form no part of the claimed design.

1 Claim, 6 Drawing Sheets
